UNITED STATES PATENT OFFICE.

ALBERT SUGDEN, OF STRATFORD, ONTARIO, CANADA.

AIRSHIP.

1,099,827.

Specification of Letters Patent.

Patented June 9, 1914.

Application filed May 14, 1913. Serial No. 767,668.

To all whom it may concern:

Be it known that I, ALBERT SUGDEN, a citizen of Canada, residing at Stratford, in the Province of Ontario and Dominion of Canada, have invented new and useful Improvements in Airships, of which the following is a specification.

This invention relates to air craft, and consists of certain novel features of construction, combination and arrangement of parts, applicable to any of the various types of air craft in use, whereby reliable and efficient sustaining, propelling and balancing means are produced.

In the accompanying drawings.—Figure 1 is a central, vertical longitudinal section of an air craft embodying my invention. Fig. 2 is a sectional plan view on the line 2—2 of Fig. 1. Fig. 3 is a vertical transverse section on the line 3—3 of Fig. 1. Fig. 4 is a sectional view of the gearing for driving and controlling one of the pairs of propellers for driving and horizontally steering the craft. Fig. 5 is a vertical section through one of the bracket yokes and parts associated with one of the pairs of propellers for driving, backing and vertically steering the craft. Fig. 6 is a vertical longitudinal section showing the means for varying the working angles of and reversing said propellers. Fig. 7 is a rear elevation of one of the front propellers of a pair of driving, backing and vertical steering propellers. Fig. 8 is a longitudinal section on line 8—8 of Fig. 7. Fig. 9 is a longitudinal section on line 9—9 of Fig. 7.

Referring to the drawings, 1 designates a boat-shaped car having a sloping forward end 2, beneath which is arranged a vertical rudder 3 for steering the machine in a horizontal plane. The said rudder is hinged or pivoted to the end 2 and is connected with operating cords or ropes 4 and 5 leading inwardly into the car and by means of which the rudder may be swung laterally in either direction.

Hollow wedge-shaped, gas filled "following" or tandem planes 6 and 7 are provided and form supporting surfaces, which may be employed or not in conjunction with a balloon or gas bag. These planes are normally inclined at an angle to the horizontal as shown. Each plane is pivotally supported from the car in advance of its transverse center by a link 8, and is pivotally connected in rear of its transverse center by a link 9

with a crank arm 10 on a transverse rock shaft 11 journaled in bearing brackets 12 on the car, said links normally extending vertically and the crank arms horizontally to support the planes in their normal inclined position adapted for straight flight. Other crank arms 13 normally project upward from the shafts 11 in a vertical plane and are connected by a longitudinally extending link rod 14, having a threaded central portion 15 passing loosely through the arms of a bifurcated bracket 16. An operating wheel or unit 17 is held between the arms of the bracket from longitudinal movement on the link rod and has a threaded hub engaging said threaded surface 15, whereby the rod may be moved either forward or backward to tilt the planes to a greater or less angle up or down whereby their angle of incidence may be varied to vary the lift or steer the machine in a vertical plane. As shown, each plane comprises a bellows-like folding or collapsible body, and said planes are provided with valved inlet and exhaust connections 6^a, 7^a, whereby hydrogen or other gas lighter than air may be supplied to inflate the planes or allowed to exhaust to deflate said planes. One or more rigid or flexible pipe 6^b may connect the planes to maintain an equalization of gas pressure therein and to also serve if desired, as braces. When the planes are inflated they serve as aerostats adapted to sustain a portion of the load weight. When said planes are deflated they act as ordinary aeroplane surfaces.

Arranged at suitable points are front and rear transverse transmission shafts 18, which carry beveled pinions 19 meshing with beveled gears 20 on shafts 21, having respectively, chain drive connections 22 with front and rear motors 23, whereby the shafts 18 are continuously driven. The ends of each transverse shaft 18 project outwardly beyond the sides of the car and are journaled in sleeves or hollow shafts 24 carrying at their outer ends bracket yokes 25, which sleeves are in turn journaled in the brackets 12 and in brackets 26 beyond the sides of the car. On the projecting ends of each shaft 18 are beveled pinions 27 meshing with similar pinions 28 on longitudinally extending propeller shafts 29, each of which has fixed thereto a pair of propellers 30 and 31, arranged one in advance of the other. The propeller shafts 29 are journaled for rota-

tion in the bracket yokes 25, which are fixed to the sleeves 24, whereby the bracket yokes are adapted to be swung or tilted in a vertical plane by rotation of the sleeves 24 about the shafts 18 as centers of motion. By the construction and arrangement described, the pairs or sets of propellers on each side of the frame are driven outwardly and in an opposite direction to the pairs or sets of propellers at the opposite side of the frame, and both sets of propellers may be tilted or inclined in the same or different directions to facilitate the propulsion and steering of the machine in either an upward or a downward direction.

Each fore propeller 30 of a pair comprises a hollow body having a front propeller blade or wing 32 arranged at one side of its center and a series of wings or rear propeller blades 33 properly pitched for propulsive effect. The hollow body is partitioned to form a spiral passage 34 extending from front to rear thereof, the front end of said passage being partially surrounded by the blade 32, while the rear end thereof is partially surrounded by one of the blades 33, said blades forming the front and rear terminal walls of the passage. It will be thus apparent that in addition to the propulsive effect of the blades, a current of air will flow through the spiral passage and form in effect a screw of air on which the propeller will travel, thereby reducing slippage and increasing the force of propulsion. As shown, the body of the propeller is provided at suitable points with air vanes 35 controlling doors or flaps 36 to regulate the discharge of air therethrough, whereby undue retention of the air is prevented.

Each rear propeller 31 of a pair comprises a hub or sleeve 37 rigidly secured to the propeller shaft, an annular rim or shield 38 forming an air channel and a series of two or more spiral blades 39 fixed to the sleeve and shield. The blades 39 are arranged so as to lie at such an angle as to cause the air to be banked or condensed within the shield, and increase the working thrust of the propeller. By mounting the propellers in pairs in the manner described, the blades of the rear propeller 31 of each pair impinge against the body of air compressed by the fore propeller 30 of the pair, whereby the propulsive force of the rear propeller is increased. As shown the rim or shield 38 is provided with vanes 41 and controlling doors or flaps 42, similar in construction to the vanes 35 and doors or flaps 36 on each fore propeller 30, whereby undue compression and accumulation of air is prevented.

In order to provide means whereby the front and rear sets of propellers at each side of the machine may be tilted in a vertical plane, and reversed to act as brakes or propel the craft backward, as well as to

provide means whereby the propellers at each side of the craft may be tilted independently of the propellers at the opposite side thereof, the following construction of controlling means is employed: The inner 70 end of the sleeve 24 of each bracket 25 is provided with a gear pinion 43, the pinions of the brackets at each side of the car being arranged to mesh with a longitudinally extending rack bar 44, toothed on its under 75 side to engage the pinions, each rack bar being mounted to slide in bearings 46. Meshing with the toothed portions of the rack bars are pinions 47 mounted upon a pair of independent transversely disposed and co-axially arranged control shafts 48, said control shafts being journaled in bearings 49 and each provided with an operating handle or lever 50, which handle or lever carries a pawl or dog 51 adapted to engage a rack 85 52, whereby each control shaft may be locked in adjusted position. By rocking the shafts 48 to equal degrees and in the same direction, forwardly or rearwardly, it will be understood that all of the bracket yokes 25 may be tilted to adjust the propellers at each side of the car to the same degree either upward or downward, so as to facilitate propulsion or steering of the craft in a vertical plane. By operating one lever 50 independently of the other, the propellers at one side of the car may be tilted while the other propellers at the opposite side of the car are held in normal position, so that the machine may be banked or its lateral stability 90 maintained. Furthermore, by simultaneously adjusting the levers 50 in opposite directions, one side set of propellers may be tilted upwardly and the other side set of propellers tilted downwardly, for maintaining lateral control or steering the machine laterally in either direction. The propellers may also be rotated within an arc of 180° to reverse them so that they will act as wind brakes to control the speed of the craft 105 when occasion requires, or so that the craft may be propelled in a backward direction. I also provide at the front and rear of the machine oppositely disposed driving and steering propellers 53, which are fixed to 110 the outer ends of shafts 54 to revolve in vertical planes. Between each pair of shafts 54 is disposed a transmission shaft 55, and on the inner ends of the shafts 54 are friction clutch members 56 adapted to be engaged by friction clutch members 57 feathered to the shaft 55. A bracket member 58 is adjustable laterally by means of a control lever 59 is provided whereby both friction members 57 may be thrown out of 115 action or either thrown into action independently of the other, by which means power may be transmitted from the shaft 55, which is constantly in action, to rotate either one of the propellers 53 for steering 120 125 130

action. The shaft 55 carries a beveled pinion 60 meshing with a pinion 61 on a longitudinal shaft 62 driven by a sprocket drive 63 from the adjacent motor 23.

5 I claim:—

An air craft including a car, separate and independent motors arranged at the front and rear of the car and having their shafts longitudinally disposed, driving propellers 10 at the sides of the car, front and rear transverse shafts for driving said propellers, gearing between said shafts and the relatively inner ends of the shafts of the motors, steering propellers at each end of the car, 15 transverse shafts for driving each set of propellers, a transmission shaft disposed

between each pair of transverse shafts, clutch devices for connecting the transmission shaft with either of said transverse shafts, longitudinally extending transmission shafts in gear with the respective transverse transmission shafts, and gearing between the longitudinal transmission shafts and the relatively outer ends of the shafts of the respective motors.

20 In testimony whereof I affix my signature in presence of two witnesses.
